UNITED STATES PATENT OFFICE.

LOUIS PROCTOR GOULD, OF AKRON, OHIO, ASSIGNOR TO MILLER RUBBER CO., OF AKRON, OHIO, A CORPORATION OF OHIO.

PROCESS AND APPARATUS FOR REMOVING EXCESS MATERIAL FROM DIPPED ARTICLES.

Application filed September 6, 1928. Serial No. 304,360.

My said invention relates to the art of coating articles by the dipping or immersion method. In coating various articles by this method, and particularly spherical or approximately spherical bodies, or those having convexly curved surfaces, great difficulty has been experienced during the draining of the surplus coating and drying thereof, in preventing the formation of a drop or hardened, 5 thickened portion on the lowest point on the surface of the article.

This invention aims to provide a simple, economical and efficient method of and means for preventing the formation of such drops or thickened portions, and the invention includes the novel method and means herein-after described and defined by the appended 10 claims.

What I at present consider a preferred or 15 desirable form of my novel apparatus is illustrated in the accompanying drawing, in which the figure is a vertical section with the article shown in elevation, the article being shown as a spherical one for purposes of illustration.

Referring by reference characters to this drawing, the numeral 1 designates a tray or table or shelf-like support having an opening 1^a provided with a plurality of pins or 20 projections 1^b (preferably three) by which the article 2 will be held spaced from the edges of the opening, the article having been coated by dipping in the coating liquid in the customary manner by means of a pair of 25 tongs or like tool, and the pins having their ball supporting ends so small as not to produce appreciable marks on the coated surface. 30 2^a indicates the drop or thickened portion, which tends to form as the surplus coating 35 liquid drains from the thus supported article.

To remove and prevent the formation of this drop, I produce an air suction adjacent the point of formation of the drop, which, of course, is the lowest point on the article. 40 This I may conveniently effect by a tube 3 having preferably a slightly flared mouth 3^a adjacent the point of drop formation to which tube suction is applied. Preferably the tube 45 communicates with a receptacle 4 for collecting surplus drained coating, which receptacle is connected to suitable means for exhausting air therefrom.

In the form shown, the receptacle is in the 50 form of a bottle supported at a convenient point beneath the table and having a stopper

4^a in which the tube 3 is adjustably supported with an air-tight fit to adapt the device to different sized balls, the stopper having another pipe or tube 5 connected to any suitable air suction device, not shown.

I have found that by thus producing suction adjacent the lowest point of the article after draining, a uniformly coated article results, as the air flowing over the surface of the ball at the adjacent this point effectually removes the drop or thickened portion.

While I have, in the present drawing, illustrated a simple form of apparatus for treating a single article, it will be obvious that it could be arranged for handling a considerable number, and also that various modifications could be made without departing from the spirit of my invention.

The most practical and economical operation of this device consists in allowing the ball to drain over the tank in which it is dipped until the liquid coating no longer drips from the ball, and to then apply the vacuum apparatus thereto to remove the last drop.

Either the vacuum device may be moved to a position beneath the ball at the time the last drop has formed, or a tray, such as 1, containing a number of balls, may be moved over the vacuum device, and the vacuum need then be applied for a few seconds only to the balls or other articles.

Having thus described my invention, what I claim is:

1. The herein described method of removing a depending drop from the surface of dipped articles, which consists in creating suction adjacent said surface at the point where the depending drop has formed.

2. The herein described method which consists in coating an article by immersion in a coating liquid, supporting the article for draining surplus coating, and applying suction adjacent the lowermost point of said article.

3. The herein described method of coating articles having convexly curved surfaces which consists in immersing the article in a coating liquid, supporting the article to allow surplus material to drain, and creating suction adjacent the bottommost point of said surface.

4. The herein described method of removing drops or thickened portions in the coating of dipped bodies of substantially spheri-

cal shape, which consists in supporting said coated bodies at isolated points, and applying suction adjacent the lowermost point of said body while the surplus coating is collecting at 5 the bottom thereof.

5. The herein described method of removing drops or thickened portions in the coating of dipped bodies of substantially spherical shape, which consists in supporting said 10 bodies at isolated points, and applying suction adjacent the lowermost point of said body while the surplus coating is forming thereon, and collecting the removed surplus material.

6. Apparatus for preventing the formation 15 of hardened drops or thickened portions on articles coated by immersion, comprising means for supporting the article at points spaced from the lowermost point thereof, and means for applying suction adjacent the said 20 lowermost point.

7. Apparatus for preventing the formation of hardened drops or thickened portions on articles coated by immersion, comprising means for supporting the article at points 25 spaced from the lowermost point thereof, and means for applying suction adjacent the said lowermost point, said suction means including means for collecting surplus material removed by suction from said article.

30 8. Apparatus for preventing the formation of hardened drops or thickened portions on dipped articles, comprising means for sup-

porting the article at points isolated from the lowermost point thereof, a closed receptacle beneath said supporting means having a restricted inlet adjacent the lowermost point of said article when on said support, and means for exhausting air from said receptacle. 35

9. Apparatus for the purpose described comprising a table-like support having an 40 opening, a plurality of article supporting projections adjacent the edge of said opening and a suction nozzle located centrally beneath said opening.

10. Apparatus for the purpose described 45 comprising a table-like support having an opening, a plurality of article-supporting projections adjacent the edge of said opening, a closed receptacle beneath said opening, a pipe connected to said receptacle and having 50 its upper end positioned to lie adjacent the lowest point of an article supported by said opening, and means for applying suction to said receptacle.

11. Apparatus for the purpose described 55 comprising an article support including a plurality of spaced projections, a receptacle located centrally below said projections, a vertical tube adjustably carried by said receptacle and communicating with the interior 60 thereof, and means for applying suction to said receptacle.

In testimony whereof, I affix my signature.
LOUIS PROCTOR GOULD.
